UNITED STATES PATENT OFFICE.

GUSTAV E. FELSENTHAL, OF NEW YORK, N. Y.

SEWING-MACHINE NEEDLE-GUARD.

1,174,973.

Specification of Letters Patent. Patented Mar. 14, 1916.

Application filed June 9, 1915. Serial No. 33,067.

To all whom it may concern:

Be it known that I, GUSTAV E. FELSENTHAL, a citizen of the United States, residing at New York, in the county of New York 5 and State of New York, have invented certain new and useful Improvements in Sewing-Machine Needle-Guards, of which the following is a specification.

This invention relates to certain new and 10 useful improvements in sewing machine needle guards.

The primary object of this invention is the provision of a needle guard readily attached to the presser foot of any sewing machine for protecting the fingers of the operator while sewing although affording an unobstructed vision of the sewing needle and the material positioned beneath the presser foot.

20 A further object of the invention is to provide a finger protecting needle guard which is cheap and easy to manufacture and which allows free visual access to the needle at all times as well as allowing a removal 25 and a rethreading thereof when desired without requiring any adjustment of the device.

A still further object of the invention is to provide a readily attached presser foot carried needle guard having a pivotal foot portion adjustably resting upon the material, which is being sewed by the needle operating within the inclosure of the guard.

With these general objects in view and 35 others that will appear as the nature of the invention is better understood, the same consists in the novel combination and arrangement of parts hereinafter more fully described, illustrated in the accompanying 40 drawings, and pointed out in the appended claims.

In the drawings forming a part of this application and in which like-designating characters refer to corresponding parts 45 throughout the several views, Figure 1 is a perspective view of one form of the device operatively mounted upon the presser foot of a sewing machine. Fig. 2 is a side elevation thereof. Fig. 3 is a horizontal sectional view thereof, and Fig. 4 is a perspective view of the guard device detached.

Referring more in detail to the drawing, the finger guard 10 is herein illustrated provided with a channel-shaped bracket 11 55 adapted to fit the shank portion 12 of a presser foot 13 and to be retained thereon by

means of a set screw 14 which is received within the slot 15 of the said bracket and by means of which screw the presser foot is secured to the presser bar 16 of the sewing machine head 17.

The sewing machine is provided with the usual needle bar 18 having a removable sewing needle 19 secured thereto by means of a screw 20, the needle being adapted for vertical reciprocations during the sewing operation within a recess 21. The bracket 11 has its forward side 22 provided with a downward extension 23 which is provided upon the side adjacent the left hand of the operator with a skeleton guard or plate 24 formed integral with the bracket and forwardly projecting at one side of the needle 19 and substantially centrally above the engaging portion of the presser foot.

75 A lug 25 is formed integral with the bracket extension 23 upon the side thereof opposite the said skeleton guard and has an L-shaped guard foot 26 pivoted thereto as at 27, and the said foot 26 has a flattened bottom 80 portion 28 normally positioned over the material which is being sewed by the needle and which material passing beneath the presser foot 13 is engaged by the guard foot 26 at the side cut-away portion of the presser foot, as 85 the presser foot is commonly constructed.

With the device thus mounted upon the presser foot, the needle 19 reciprocates within the socket 21 of the presser foot between the skeleton guard 24 and the guard foot 26 90 so that neither hand of the operator can be brought accidentally beneath the needle on account of the oppositely positioned guard members which members also project forwardly of the needle although allowing free 95 access at all times to both the needle and the material which is being sewed thereby. The pivoted guard foot 26 automatically accommodates itself to the thickness of the material being sewed and which passes thereunder and the same may be thrown backward if desired by means of the finger hold 29 upon the upper free end thereof.

100 It will thus be seen that an inexpensive guard is provided which constitutes a safety device for protecting operators of sewing machines, while interfering in no manner with the efficient operation of the machine.

While the form of the invention herein shown and described is what is believed to 110 be the preferred embodiment thereof, it is nevertheless to be understood that minor

changes may be made without departing from the spirit and scope of the invention as claimed.

What is claimed as new is:—

- 5 1. A sewing machine guard comprising in combination with a presser foot and a set screw therefor, a bracket seated upon the presser foot in engagement with the said screw, a needle reciprocatingly mounted adjacent the said presser foot, a forwardly projecting skeleton guard carried by the bracket at one side of the needle, an integral lug upon the said bracket at the opposite side of the needle from the said skeleton guard, a 10 downwardly and forwardly projecting L-shaped guard foot pivoted to the said lug and having a bottom material-engaging portion in the same plane as the engaging portion of the presser foot, and a turned-over 15 hand hold at the upper forward end of the said guard foot.
2. A needle guard for sewing machines comprising a bracket for inclosing the shank portion of a machine presser foot, a fixed skeleton guard and a vertically swinging pivotal guard foot forwardly carried by the said bracket upon opposite sides of the machine needle and providing an unobstructed 20 open space therebetween.
3. A needle guard for sewing machines comprising a bracket adapted for removable attachment to the machine presser foot rearwardly of the needle of the machine, an integral skeleton guard plate at one side of 25 the said bracket, a lug at the opposite edge thereof, an L-shaped guard foot pivoted for vertical movements upon the said lug and adapted to seat forwardly of the presser foot upon the goods to be operated upon, the said guard foot and plate adapted to 30

project forwardly of and upon opposite sides of the sewing needle of the machine.

4. A sewing machine guard comprising in combination with a presser foot having a cut-away side portion, a bracket seated upon the presser foot, a needle reciprocatingly mounted adjacent the said presser foot, a forwardly projecting skeleton guard carried by the bracket at one side of the needle, and a depending L-shaped guard foot pivotally carried by the bracket for vertical movement at the opposite side of the needle and having a flattened bottom portion normally positioned within the said cut-away side portion of the said presser foot. 55

5. A device of the class described comprising in combination with a sewing machine presser foot having a side cut-away portion and a sewing needle, a downwardly-forwardly projecting L-shaped guard foot pivotally mounted upon the said presser foot and having a bottom material-engaging portion in the same plane as the engaging portion of the presser foot, and a turned-over hand hold at the upper forward end of the 60 said guard foot.

6. A device of the class described comprising an angular bracket provided adjacent one side thereof with a downwardly and forwardly projecting L-shaped guard foot pivotally mounted and adapted for yieldingly seating upon the goods to be operated upon, and a skeleton guard upon the said bracket opposite the said foot-carried side thereof. 70

In testimony whereof I affix my signature 75

GUSTAV E. FELSENTHAL.
